UNITED STATES PATENT OFFICE.

CHARLES H. EDDY, OF ATTLEBORO, MASSACHUSETTS.

COMBINED SHADE AND CURTAIN FIXTURE.

1,333,163.

Specification of Letters Patent.

Patented Mar. 9, 1920.

Application filed December 18, 1917. Serial No. 207,774.

To all whom it may concern:

Be it known that I, CHARLES H. EDDY, a citizen of the United States, residing at Attleboro, in the county of Bristol, State of Massachusetts, have invented certain new and useful Improvements in Combined Shade and Curtain Fixtures; and I do hereby declare the following to be a full, clear, and exact description of the invention, 10 such as will enable others skilled in the art to which it appertains to make and use the same.

This invention relates to improvements in removable curtain and shade fixtures for 15 windows and particularly to devices of this character which do not require the use of nails or screws.

One object of the present invention is to provide an improved device of this character 20 which is so constructed that the attachment thereof to the frame or casing of a window can be accomplished in a small space of time and which is capable of adjustment to fit any window frame and for 25 any length of shade and curtain pole.

Another object is to provide a device of this character wherein the major portion of the fixture is formed from a single metal blank.

30 Other objects and advantages will be apparent from the following description when taken in connection with the accompanying drawing.

In the drawing:

35 Figure 1 is a front elevation of the invention applied to a window casing, and supporting a shade and curtain pole.

Fig. 2 is a vertical sectional view taken on the line 2—2 of Fig. 1.

40 Fig. 3 is a perspective view of one of the fixtures removed from the window.

Fig. 4 is a plan view of the blank from which the major portion of the device is formed.

45 Referring particularly to the accompanying drawing, 10 represents the upper transverse member or heading of the window frame or casing to which my invention is particularly adapted for attachment.

50 The fixture includes a major portion A formed from a single piece of sheet metal, a spring member B and a curtain supporting hook C.

The member A has a body portion 11 from 55 the upper edge of which there extend the tabs 12, said tabs being bent at right angles

to the body at 13, and the outer end of said tab is bent downwardly at right angles to the tab and formed with the tangs 14 which are adapted to bite into the upper face of 60 the before-mentioned heading of the window casing. Formed integrally on the outer vertical edge of the body is a tab 15 which is bent inwardly onto the face of the body portion and is cylindrical in cross section. 65 The tab is thus in the form of a vertical tubular socket into which is disposed the inner vertical portion of the shank of the hook member 16. This hook member is preferably Z-shaped and has its vertical 70 outer portion 17 adapted to be received in a vertical opening formed in one end of the section 18 of the tubular and telescoping curtain pole D.

Struck out from the body, directly below 75 the socket member 15, is a shade pintle receiving bracket arm 19. From the lower edge of the other end of the body there is bent outwardly an apertured lug 20 in which is engaged one end of a coil spring 21. Connected to the other end of this spring is a hook 22 the bill of which is provided with a sharp point for biting engagement in the lower face of the heading of the window casing.

80 From an inspection of the drawing, it will be seen that the elements above described, are duplicated at the other side of the window, and are exactly like those just described, except that the shade bracket arm 90 is provided with an open-ended slot 23 for the flat pintle of the shade roller 24.

The manner of applying the fixtures to the window casing will be readily understood from the drawing and it is not thought 95 necessary to explain the same herein.

Struck out from the edge of the blank above the tab 15 is a second shorter tab 15' which is arranged to extend at right angles from the face of the body of the device and 100 serve as a stop to prevent the outwardly swinging movement of the Z-shaped members.

What is claimed is:

A sheet metal blank for forming a combined window shade and curtain fixture comprising an elongated body having a pair of tapering tongues extending from one of the longer sides thereof, the terminals of the tongues being formed with prongs, the edge 105 of the body between the tongues being inwardly curved, an apertured tab formed on

the other side of the body and adjacent one
end, a pair of tabs formed on one end of the
body and of different lengths and in close
proximity to each other, a projection formed
5 on the other end of the longer side of the
body remote from the apertured tab and
having an elongated member extending
longitudinally of the body and separated by
a line of cut in the semblance of a compound

curve, the outer edge of said member being 10
similarly cut, the same member having an
aperture in its outer end.

In testimony whereof, I affix my signature
in the presence of two witnesses.

CHARLES H. EDDY.
